(57) **CLAIM**

The ornamental design for a controller for computer, as shown and described.

DESCRIPTION

FIG. 1 is a front view of a controller for computer showing our new design;

FIG. 2 is a back view thereof;

FIG. 3 is a top view thereof;

FIG. 4 is a bottom view thereof;

FIG. 5 is a right view thereof; and,

FIG. 6 is a left view thereof.

The broken lines depict portions of the controller for computer that form no part of the claimed design.

1 Claim, 6 Drawing Sheets
